UNITED STATES PATENT OFFICE.

JOHN D. PETTIT, OF HOLLYWOOD, CALIFORNIA.

COIN TILL.

Application filed June 22, 1921. Serial No. 479,525.

To all whom it may concern:

Be it known that I, JOHN D. PETTIT, a citizen of the United States, and a resident of Hollywood, in the county of Los Angeles and State of California, have invented a new and Improved Coin Till, of which the following is a description.

The general object of my invention is to provide a coin holder or till adapted to hold 10 coins of various denominations in stacks and constructed and arranged to promote strength with simplicity of construction and so arranged as to promote convenience in the placing and removal of the coins.

Reference is to be had to the accompanying drawings forming a part of this specification, it being understood that the drawings are merely illustrative of one example of the invention.

20 Figure 1 is a top view of a coin till embodying my invention;

Figure 2 is a front view thereof;

Figure 3 is a bottom view;

25 Figure 4 is a horizontal section on the line 4—4, Fig. 2;

Figures 5 and 6 are transverse vertical sections respectively on the lines 5—5 and 6—6, Figure 1;

Figure 7 is a fragmentary rear view;

30 Figure 8 is a sectional perspective view showing a detail of the coin till at the top;

Figure 9 is a perspective view showing the till in position on a counter.

The device may be secured to a cash-drawer, or may be secured to a counter to lie flush with the latter as is shown in Figure 9.

In carrying out my invention in accordance with the illustrated example, the top 40 10, back 11 and bottom 12 are formed integrally and stamped up from sheet metal. The back at the central portion is depressed as at 13 to permit the till to slip or fit over the usual lock-cylinder generally found on 45 the outside of a cash-drawer and make a close and tight fit against the drawer. At the back adjacent to the side edges are similar depressions 14, the depressed portions having a vertical series of key-hole slots 15 50 where by the device may be engaged with projecting screws on the supporting structure. By forming the slots 15 in the depressed portions, the back fits snugly against the structure to which it is fastened and at 55 the same time resiliency is given the part in which the key-hole slots are formed to

thereby give a better engagement of the back with the engaged screws or the like.

The ends 16 and front 17 are formed integrally and separate from the top, back 60 and front element. Integral also with the front 17 is a series of vertical tubes 18 to receive coins of various denominations in stacks. The front is formed with a vertical sight slot or opening 19 at each coin tube 65 18 for readily noting the amount of coins in the respective stacks. Round openings 20 are formed in the top 10 in register with the columns for the placing of the stacks of coins, the material at the top being formed 70 with depending annular flanges 20^a at each opening 20, said flanges snugly fitting within the upper ends of the tubes 18 to firmly hold the latter. The bottom 12 is formed 75 with depressions, 21, at the bases of each tube 18, the depressed portions being rounded at the inner ends as clearly seen in Figure 3 to snugly receive within the depressed portions the lower ends of the columns 18. Thus, the flanges 20^a at the upper ends of 80 the columns fit within the columns whereas the metal at the depressed portions 21 extend at the outside of the columns. The depressed portions 21 are open at the front for the removal of the lowermost coin in a 85 column and said depressed portions are formed with longitudinal slots 22 extending from the front of the till for the convenient grasping of the coin to be removed. As a further bracing for the columns a portion 90 of the material cut to form the slots 22 is upturned as at 23 to lie against the backs of the columns 18.

To secure the top 10 to the front 17, said top is formed with locking flanges 24 between the slots 19, and the upper edge of the front is formed with flanges 25 which are bent into U-shape and engaged with the flange members 24 by a seamed connection between the front and the top. Similarly, 100 the lower edge of the front 21 is formed with upturned flanges 26 about which are seamed the U-shaped flanges 27 formed on the bottom 12. Thus, the till is formed of two members, the one including the top 10, 105 back 11, and bottom 12, and the other, the ends 16, front 17, and columns 18, the two elements being seamed together as described to form a unitary structure and at the same time to firmly hold the columns 18 against 110 displacement.

I would state in conclusion that while the

illustrated example constitutes a practical embodiment of my invention, I do not limit myself strictly to the mechanical details herein illustrated, since manifestly the same can be considerably varied without departure from the spirit of the invention as defined in the appended claims.

Having thus described my invention, I claim:

10. 1. A coin till including a sheet metal element forming the top, back and bottom of the till, and a second element forming the front and ends of the till, said front having integral tubular columns at the inner side thereof, and being seamed to the top and bottom, and the top having openings in register with said columns, the bottom of the till having depressions below the general plane of the bottom within which the lower ends of the columns are received, the top presenting annular depending flanges extending within the upper ends of the columns, said depressed portions being open at the front for the removal of the lowermost coins in the stacks.
20. 2. A sheet metal coin till adapted to receive tubular columns in which coins may be stacked, the top of the till having openings in register with said columns, the back of

said structure having a central depression to 30 accommodate a cash-drawer lock-cylinder and having additional vertical depressions at the sides, said depressed side portions having key-hole slots therin for engagement of the back with headed supporting 35 elements.

3. A coin till formed of sheet metal having tubular columns in which coins may be stacked, a bottom therefor, said bottom having depressions between the general plane 40 thereof for accommodating within the same the lower ends of the columns, the front ends of said depressed portions being open for the removal of the coin and there being transverse slots in said transverse portion to permit of the coin being grasped.

4. A sheet metal coin till, the top, back and bottom of which are formed integral, and the front and ends being formed integral in a separate element, said front having at the inner side thereof integral coin-receiving columns and presenting vertical sight slots in said columns, together with series of flanges respectively on the front and on the top and bottom seamed together 55 between the sight columns.

JOHN D. PETTIT.
